UNITED STATES PATENT OFFICE.

MAX BENDICK, OF NEW YORK, N. Y.

MACHINE FOR PERFORATING PAPER PATTERNS.

SPECIFICATION forming part of Letters Patent No. 398,572, dated February 26, 1889.

Application filed March 5, 1888. Serial No. 268,207. (No model.)

To all whom it may concern:

Be it known that I, MAX BENDICK, of the city, county, and State of New York, have invented certain new and useful Improvements in Machines for Perforating Paper Patterns; and I do hereby declare that the following is a full and exact description thereof, reference being had to the accompanying drawings, and to the letters of reference marked thereon, making a part of this specification, in which—

Figure 1 is an elevation of my improved pattern-perforating machine attached to a table; Fig. 2, a detail of the upper end of the supporting-rod and adjustable pulley thereon; Fig. 3, a detailed longitudinal section through the perforating-needle in line $x-x$ of Fig. 1; and Fig. 4, a horizontal section in line $y-y$ of Fig. 1, giving a plan view of the hand plate or base.

The object of my invention is to provide a firm, stable, yet readily-movable support for a stencil-perforating needle which is geared by an elastic cord with a revolving pulley.

It consists in the novel devices hereinafter described and claimed, whereby the desired end is fully attained.

In the accompanying drawings, A represents the table or stand upon which the paper or stencil-board to be perforated is placed; B, a screw-clamp adapted to be readily attached and made fast to the edge of a stand or table; C, a stud-axle carried upon an arm or bracket projecting outwardly from the clamp; D, a crank wheel or pulley revolving upon said stud-axle; E, a treadle, and F a connecting-rod by which the treadle is coupled to the wrist-pin G of the crank-wheel, so that the wheel may be driven by the play of the treadle.

The upper bar of the screw-clamp, which projects over and upon the top of the table, is formed with a socket-piece and socket, H, at its end, adapted to receive and firmly hold a detachable rod, I, the socket being inclined so as to cause the rod inserted therein to project upwardly at an inclination with the table sufficient to carry its upper end inwardly from the edge to which the clamp-screw is attached, as shown in Fig. 1. To the upper end of this inclined rod is fitted a longitudinal

screw, J, working through ears or side plates, K K, fixed to the rod, whereby a longitudinal adjustment may be made of the screw upon the rod, it being fixed when adjusted by means of lock-nuts L L, working upon the screw 55 against opposite sides of one of the ears K, as shown in Fig. 2. The outer end of the screw J terminates in a yoke, J', affording pivotal bearings for the ends of a transverse axial shaft or spindle carrying two grooved pulleys, 60 M N, of different diameters. The pulley N is geared by a cord, O, with the crank wheel or pulley D, the tension of the cord being regulated by the longitudinal adjustment of the screw J. 65

Represents the reciprocating needle bar or rod, having a socket in its lower end, in which the perforating-needle P' is secured in the customary manner by means of a set-screw, i, or other device. This needle-bar is made to 70 reciprocate freely in a standard, Q, upheld in a vertical position at a right angle to the face of the table A, upon which the work is placed by means of a bracket-bar, R, projecting at an angle from a flat base-plate or hand-plate, S, 75 adapted to rest firmly upon and move freely over the table, and which is preferably made wide enough to allow the fingers or some portion of the hand of a person holding the standard to rest or bear thereon and hold it 80 down in place upon the table. The upper end of the standard Q terminates in a yoke, T, affording bearings for the end of a transverse shaft, U, formed with a crank, U', to which the upper end of the needle-bar is coupled, 85 and carrying a pulley, W, which is geared to the pulley M at the outer end of the inclined rod I by means of an elastic cord, Y, which permits the needle to be freely moved to and fro over the table in all directions within a 90 limited radius under the pulley N, while in constant gear therewith.

When the needle is not in use, it may be hung up, as illustrated by dotted lines in Fig. 1, upon a hook, X, attached for the purpose to 95 the rod I.

In the use and operation of the needle the driving wheel or pulley D is attached by means of the clamp-screw B to the table A, upon which the work is to be placed, and the 100

treadle E is connected thereto. The rod I is then inserted and secured in its socket H and the cord O led over the pulleys D and N, and its tension properly adjusted by means of the 5 adjusting-screw J, which carries said pulley N. The elastic cord Y is next led over the pulleys W and M and the apparatus is in readiness for use. The stencil-paper to be perforated is laid upon the table A under the end of the 10 rod I, the base-plate S of the needle placed thereon, and, the needle-standard Q being clasped with the first and second fingers, the needle may be guided in any direction over the paper and readily made to follow the lines 15 of a pattern of any description. The wide flat base-plate S serves to steady the standard and to constantly keep the needle-bar and needle at a right angle to the surface of the paper to be perforated. While the needle is 20 thus guided over the lines of the pattern it is kept in rapid oscillation by the play of the operator's foot upon the treadle E, so as to cause it to puncture the underlying paper with a continuous row or line of minute per-

forations, the constant connection of the crank 25 operating the needle with the driving-wheel operated by said treadle being maintained as the needle is made to traverse the paper by means of the elasticity of the cord or belt Y.

I claim as my invention and desire to set 30 cure by Letters Patent—

The combination, with a reciprocating stencil-perforating needle and the case inclosing the same, of the flat extended base-plate and the interposed bracket-bar connecting the 35 plate and case, whereby the needle is upheld in a vertical position by the base-plate independently of other support, substantially in the manner and for the purpose herein set forth.

In testimony whereof I have signed my name to this specification in the presence of two subscribing witnesses.

M. BENDICK.
